UNITED STATES PATENT OFFICE.

HENRY W. MUHLEISEN AND CLEMMEN LUND, OF LOS ANGELES, CALIFORNIA; SAID MUHLEISEN ASSIGNOR OF HIS RIGHT TO WILLIAM S. RUSH, OF LOS ANGELES, CALIFORNIA.

TIMER.

1,305,559.

Specification of Letters Patent. Patented June 3, 1919.

Application filed October 21, 1918. Serial No. 259,033.

To all whom it may concern:

Be it known that we, HENRY W. MUHLEISEN and CLEMMEN LUND, citizens of the United States, residing at Los Angeles, in the county of Los Angeles and State of California, have invented new and useful Improvements in Timers, of which the following is a specification.

Our invention relates to a timer or commutator for use in connection with multi-cylinder engines.

The object of our invention is to provide a timer of the Ford type that will be simple in construction and positive in its action.

Another object is to provide a timer with a combined rolling and sliding contact action which will keep the contact surfaces clean and insure perfect electrical connection between the generator and spark plugs.

With these and other objects in view, our invention consists in the construction, combination and arrangement of parts herein-after described and claimed.

In the accompanying drawings which form a part of this specification,

Figure 1 is a plan view of a timer, embodying the principles of our invention, with part of the casing broken away and shown in section.

Fig. 2 is a view in side elevation of the timer shown in Fig. 1 with parts broken away and shown in section.

Fig. 3 is a detailed sectional view on the line 3—3 in Fig. 1, showing the contact roller, its mounting parts and its controlling spring.

The timer is of a Ford type and comprises a casing 10 within which is fixed an insulating ring 11 in which contact plates 12 are embedded. These contact plates connect with binding posts 13, the binding posts being insulated from the casing by bushings 14. A cam shaft 15 turns in the center of the casing. A sleeve 16 having two parallel

radial bearing lugs 17 and 18 formed integral with it, is keyed to the cam shaft within the casing and is held thereon by a nut 19, which screws on the end of the shaft.

A roller arm 20 having a pivot pin 21 at one end which extends through the bearing lugs 17 and 18 has a pivot screw 22 fixed in its free end upon which a flanged roller 23 is mounted, the head 24 of the pivot screw serving to hold the roller in place. As shown in Fig. 2, roller 23 is adapted to

travel inside the insulating ring 11 and contact with contact plates 12. It has an end flange 25 adapted to press against the inner edge 26 of the insulating ring 11. A retractile coil spring 27 having one end fixed in bearing lug 17 and the other in the pivot pin 21 serves the double purpose of holding the roller 23 against the insulating ring 11 and contact plates 12 by its unwinding tension and holding the flange 25 against the edges of the insulating ring 11 and contact plates 12 by its retractile tension, the latter acting to withdraw pivot pin 21 from bearing lugs 17 and 18.

Operation: As the cam shaft 15 turns in the direction indicated by the arrow *a*, the sleeve 16 and bearing lugs 17 and 18 formed integral therewith are carried around with it. The roller arm 20 pivoted in lugs 17 and 18 and the roller 23 attached thereto are thus caused to revolve around the cam shaft. The spring acts through the roller arm to press the roller against the inner periphery of the insulating ring 11 and the contact plates 12, in the direction indicated by arrow *b*, by its unwinding tension and at the same time acts to press the roller flange 25 against the inner edges of the insulating ring 11 and contact plates 12 in the direction indicated by arrow *c* by its retractile tension. A rolling contact is thus produced between the roller and plate faces while a combined rolling and sliding contact is produced between the roller flange and the edges of the contact plates. This combined rolling and sliding contact insures a bright contact surface and a consequent reliable electrical connection.

While we have shown the preferred construction of our timer as now known to us, it will be understood that various changes in the construction, combination and arrangement of parts may be made by those skilled in the art without departing from the spirit of our invention as claimed.

We claim:

A timer, comprising a casing; an insulating ring fixed in the casing; contact plates embedded in the insulating ring; binding posts connected to the contact plates; a cam shaft rotatably mounted through the center of the casing; a sleeve keyed upon the cam shaft within the casing; two radial bearing lugs extending from the sleeve; a roller arm fitting against the outer face of one lug; a pivot pin extending from the roller arm

2

through the lugs; a roller carried by the roller arm and adapted to travel inside of the insulating ring and engage the contact plates, and having an end flange adapted to 5 press against the inner edge of the insulating ring; and a coil spring mounted upon the pivot pin between the bearing lugs, one end of the spring being connected to a lug and the other end of the spring being connected to the pivot pin, the tension of the 10

spring being exerted to hold the roller against the insulating ring and contact plates and to hold the flange against the edges of the insulating ring and contact plates.

15

In testimony whereof we have signed our names to this specification.

HENRY W. MUHLEISEN,
CLEMMEN LUND.
